UNITED STATES PATENT OFFICE

2,491,267

TYPEHOLDER FOR PRINTING PRESSES

Frederick B. Jorgensen, Piedmont, Calif.

Application June 10, 1946, Serial No. 675,575

8 Claims. (Cl. 101—381)

1

This invention relates to type frames, of the character used in box printing machines, and is an improvement over the similar structure in my prior Patent No. 1,801,507, issued April 21, 1931.

An object of the invention is to provide, in a frame of the class described, a double lock feature for securing the type-holding and spacer bars to the frame so as to insure against their detachment from the frame during printing operations.

Another object of the invention is to provide a type frame for rotary printing presses capable of being loaded through gates disposed intermediate its longitudinal sides rather than from an end as in previously proposed devices.

A further object of the invention is to provide, in a type frame of the character described having associated therewith a plurality of separate typeholding and spacer bars, a single bolt element for locking all of the bars to the type frame.

The invention possesses other objects and features of advantage, some of which, with the foregoing, will be set forth in the following description of the preferred form of the invention which is illustrated in the drawings accompanying and forming part of the specification. It is to be understood, however, that variations in the showing made by the said drawings and description may be adopted within the scope of the invention as set forth in the claims.

Referring to the drawing:

Figure 1 is a top plan view of the type holder of my invention.

Figure 2 is a vertical sectional view taken in the plane indicated by the line 2—2 of Figure 1.

Figure 3 is a vertical sectional view taken in the plane indicated by the line 3—3 of Figure 1.

Figure 4 is a portional vertical sectional view, to an enlarged scale, taken in the plane indicated by the line 4—4 of Figure 1.

Figure 5 is a portional vertical sectional view, to an enlarged scale, taken in the plane indicated by the line 5—5 of Figure 1.

Figure 6 is a side elevational view looking in the direction of the arrow 6 of Figure 5.

The illustrated embodiment of my invention is seen to comprise a rectangular base plate 7 having a substantially semi-circular cross-sectional form to permit its mounting on the type cylinder of a rotary press. The actual mounting on the press cylinder may be effected in a manner well known in the art and since it has no bearing on the present invention is not illustrated or described herein. The base plate 7 is of

2

uniform thickness throughout its area and has a pair of grooves 8 extending along the convex surface thereof and paralleling the respective longitudinal edges 9. Arcuate margin bars 11, rising from the convex surface of the base plate, are suitably secured to the opposite transverse ends of the latter and comparable margin bars 12 are suitably secured to and extend along the longitudinal edges of the plate. Each of the longitudinal margin bars 12, as will be seen in Figure 3, is provided with an integral lip portion 13 spaced from the surface of the base plate 7 and having, at its junction with the main body of the margin bar, a relatively perpendicular surface 14 which is aligned and coplanar with the side of the groove 8 nearest the longitudinal edge 9 of the base plate. The disposition of the parts is such that parallel L-shaped grooves are thus formed along the holder, the longer leg of the L paralleling the convex surface of the base plate while the shorter leg, represented by the groove 8 extends radially inwardly toward the center of curvature of the base plate. A section of each longitudinal margin bar 12 intermediate the ends 15 of the latter, and defined by the spaced surfaces 16, is omitted to provide a loading gate which is adapted to be opened or closed by the provision of a detachable section 17 which has a cross-sectional form identical with that of the margin bar 12. Means for positioning and securing the sections 17 in place are provided in dowel pins 18, secured in the base plate and slidably engaged in complementary apertures 19 provided in the sections 17, and in capscrews 21 which pass 20 through suitable apertures 22 formed in the sections 17 and which are screwed into threaded sockets 23 provided in the base plate 7. The heads of the screws 21 are set in counterbores 24 so as to position the heads below the surface of the sections 17. Since the sections 17 are similar to form to the margin bars 12 it will be seen that the L-shaped grooves are continued along the entire length of the holder between the end margin bars 11. It will also be seen, in Figures 4 and 5, that the side of the groove 8 nearest the edge 9 of the base plate is provided with a bevel 26 which extends only between the limiting surfaces 16 of the gates and whose purpose will be presently described.

I provide type carrier by means of which any desired arrangement of printing type may be attached to the holder and I further provide a single element means for "locking up" the type composition so as to prevent displacement thereof. Each carrier 27 comprises a bar which is longi-

tudinally curved to conform with the surface curvature of the base plate 7 and which is provided with an inverted T-shaped groove 28 extending entirely along its convex surface and opening at the opposite ends of the bar. Into this T-shaped groove may be inserted, from either open end thereof, complementarily shaped type and space blocks 29 selected ones of which may carry printing characters 31. Sufficient blocks 29 are associated with each carrier so as to completely fill the groove 28 from end to end. As will be best seen in Figures 4 and 5, each end of the carrier is provided with an integral extension 32, projecting into the space between the lip portion 13 of the longitudinal margin bar and the adjacent surface of the base plate, the extreme end of the extension 32 being provided with an integral hook portion 33 complementary with and entering the groove 8. The type carrier, by this arrangement, possesses interlocking connection with the holder unit. Spacing bars 34, of a vertical thickness equal to that of the type carriers 27 and having end structures similar to that just described in connection with the type carriers, are provided for insertion between adjacent type carriers so as to effect an interlinear spacing between the type of the respective carriers. A lock-up bar 36 is provided which is identical in every respect with the spacing bars 34 with the exception that it carries a locking bolt 37 whose stem passes through an elongated slot 38 provided in and extending longitudinally of the base plate 7. An enlargement 39 of the slot 38 is recessed into the concave surface of the base plate and receives the flat sides of the bolt head 41 so that the latter will be prevented from rotating as the bolt nut 42 is tightened or loosened. The nut 42 is set into a counterbore 43 so that the former will not project beyond the surface of the lock-up bar.

Attachment or detachment of the type carriers, spacing bars and lock-up bar to and from the holder unit may be effected by removing the longitudinal margin bar sections 17 so as to expose end portions of the L-shaped side grooves of the unit. The various bars may then be caused to slide along the grooves until the extensions 32 register with the gaps created by the detached sections 17 whereupon the bars may be lifted from the holder unit. Attachment or rearrangement of the various bars may be accomplished by reversing this procedure. However, before a bar can be released from the holder unit, as will be seen in Figures 4 and 5, it is necessary to free the hook portions 33 from the grooves 8. Since each bar has a considerable amount of longitudinal flexibility, this detachment may be readily accomplished by inserting a suitable prying tool, such as a screwdriver or knife, into the recess formed by the face of the bevel 26 and the confronting surface of the hook 33 and prying radially outwardly of the holder unit so as to effect a chordal expansion of the bar sufficient to allow the hook element to clear the groove 8 whereupon the bar may be lifted from the holder unit. It is obvious therefore that, in applying the various bar elements to the holder unit, a radial pressure applied to the elements when the latter are properly aligned with the unit will cause the ends of the elements to be sprung apart and to thereafter snap into the grooves 8. Thus the bar elements will be securely locked to the holder unit until deliberately released as above described.

The double lock described above, comprising

the extension members 32 and the hook elements 33 which engage their respective grooved recesses, functions to provide an increased measure of operational safety for the printing press with which the type holder unit may be employed. In the printing of comparatively unyielding material such as wooden box ends considerable pressure is imposed on the type carrier and frequently, in the event that slippage occurs between the imprinted material and the press platen, the type carrier is buckled behind the material sufficiently to release the means attaching the carrier to the holder, the carrier being then flung from the holder. In the improved holder of my invention such accidental detachment is not possible.

Another feature of advantage, the provision of a single bolt lock for securing the various type carriers and spacer bars in place and in proper relationship, tends to materially speed up composing operations and to remove the possibility of unequal pressure strains which multiple locking bolts might cause. For purposes of convenience, the heads of the screws 21 and the nut 42 possess the same dimensions so that the same socket wrench may be used on each.

A further feature of my invention, it will be noted, is the ease with which type bars and spacer bars may be inserted in or removed from the carrier while the latter is mounted on the press drum. This serves to greatly expedite the process of changing type setups between different jobs and preserves registry and alignment of the composition and the material on which the impression is to be made.

Having thus described my invention in detail, what I claim as new and desire to secure by Letters Patent is:

1. A type holder for printing apparatus comprising a base plate, margin bars on and extending along opposite edges of said base plate, said margin bars and base plate having portions thereof formed to provide grooves paralleling said opposite edges of the base plate and each groove having cross-sectional portions thereof extending in different directions, sections of said margin bars being removable to expose portions of said grooves, bar elements having portions thereof complementarily shaped with respect to and slidably engageable in said grooves, and means for securing said bar elements against slidable movement in said grooves and relative to said base plate.

2. A type holder for printing apparatus comprising a base plate, margin bars on and extending along opposite edges of said base plate, said margin bars and base plate having portions thereof formed to provide grooves paralleling said opposite edges of the base plate and each groove having cross-sectional portions thereof extending in different directions, gates comprising displaceable sections of each margin bar, bar elements attachable and detachable to and from said type holder through said gates and having portions thereof complementarily shaped with respect to and slidably engageable in said grooves, means for releasably securing said displaceable sections of the margin bars to the base plate to close said gates, and means for securing said bar elements against slidable movement in said grooves and relative to said base plate.

3. A type holder for printing apparatus comprising a base plate having grooves therein paralleling each other and opposite edges of said base plate, transverse margin bars secured to said base plate and extending along sides of the latter in-

tersecting said grooves, longitudinal margin bars secured to said base plate and extending along said opposite edges of the base plate, said longitudinal margin bars having portions thereof spaced from the surface of the base plate and overlying said grooves, bar members overlying said base plate and having portions engaged in the spaces between said longitudinal margin bars and said base plate and in said grooves, and gates comprising removable portions of a pair of said margin bars through which said bar members may be engaged with and detached from the type holder.

4. A type holder for printing apparatus comprising a base plate having grooves therein paralleling each other and opposite edges of said base plate, transverse margin bars secured to said base plate and extending along sides of the latter intersecting said grooves, longitudinal margin bars secured to said base plate and extending along said opposite edges of the base plate, said longitudinal margin bars having portions thereof spaced from the surface of the base plate and overlying said grooves, bar members overlying said base plate and having portions engaged in the spaces between said longitudinal margin bars and said base plate and in said grooves, gates comprising portions of a pair of said margin bars removable from other portions of the margin bars and through which said bar members may be engaged with and detached from the type holder, and means associated with one of said bar members for immovably securing the latter to said base plate.

5. A type holder for printing apparatus comprising a base plate having grooves therein paralleling each other and opposite edges of said base plate, transverse margin bars secured to said base plate and extending along sides of the latter intersecting said grooves, longitudinal margin bars secured to said base plate and extending along said opposite edges of the base plate, said longitudinal margin bars having portions thereof spaced from the surface of the base plate and overlying said grooves, bar members overlying said base plate and having portions engaged in the spaces between said longitudinal margin bars and said base plate and in said grooves, gates comprising detachable portions of each of a pair of said margin bars intermediate the ends thereof through which said bar members may be engaged with and detached from said type holder, means for releasably securing said detachable margin bar portions to said base plate, and means associated with one of said bar members for securing the latter to and at a selected position relative to the base plate.

6. A type holder for printing apparatus comprising a base plate, margin bars on and extending along opposite edges of said base plate, said margin bars and base plate having portions thereof formed to provide substantially L-shaped grooves paralleling said opposite edges of the base plate, sections of said margin bars intermediate the ends thereof being removable to expose portions of said grooves, bar elements having sub-

stantially L-shaped portions thereof slidably engageable in said L-shaped grooves, and one of said bar elements having means engaging said base plate for securing all of the bar elements against movement relative to said base plate.

7. A type holder for printing apparatus comprising a base plate, margin bars on and extending along opposite edges of said base plate, said margin bars and base plate having portions thereof formed to provide substantially L-shaped grooves paralleling said opposite edges of the base plate, and having closed opposite ends, sections of said margin bars intermediate the ends thereof being removable to expose cross-sectional portions of the L-shaped grooves and to provide gates through which access may be had to said grooves, bar elements having substantially L-shaped portions thereof insertible through said gates, into registry with said grooves and into slidably engagement with said grooves, means carried by one of said bar elements engaging said base plate, and means for securing said removable margin bar sections to said base plate to close said gates.

8. A type holder for printing apparatus comprising a base plate having grooves therein paralleling each other and opposite edges of said base plate, transverse margin bars secured to said base plate and extending along sides of the latter intersecting said grooves, longitudinal margin bars secured to said base plate and extending along said opposite edges of the base plate, said longitudinal margin bars having recessed edge portions thereof overlying the grooves of the base plate and forming with the latter composite L-shaped grooves, sections of said longitudinal margin bars intermediate the ends thereof being removable to form gates exposing and providing access to said L-shaped grooves, means to secure said removable sections of the longitudinal margin bars to the base plate to close said gates, bar elements having L-shaped portions thereof insertible into said L-shaped grooves through said gates and when the latter are open, said grooves of the base plate in the portions thereof extending across said gates each having one side surface thereof angularly bevelled to clear portions of the L-shaped sections of said bar elements to effect engagement and disengagement of the latter L-shaped sections with the grooves of the base plate, and means carried by one of said bar elements and engageable with said base plate at a selected position on the latter for securing all of the bar elements against movement relative to said base plate.
